HIGH SPEED FALSE TWIST SPINDLE DRIVE
 Richard G. Hilbert, Smithfield, R.I., assignor to Leesona Corporation, a corporation of Massachusetts
 Original application June 16, 1958, Ser. No. 742,234, now Patent No. 3,044,247, dated July 17, 1962. Divided and this application Nov. 7, 1961, Ser. No. 150,812
 2 Claims. (Cl. 57—104)

The present invention relates to textile machinery and is directed more particularly to a machine for imparting false twist to a strand of yarn. This application is a division of applicant's prior copending application Serial No. 742,234 filed June 16, 1958, now U.S. Patent No. 3,044,247.

In recent years, much attention has been given by the textile art to the so-called "crimped" synthetic yarns. As is well known, these yarns have been mechanically treated to assume a crimped or coil-like configuration so that they have a certain inherent elasticity and bulkiness that distinguishes them from untreated yarns. These properties cause them to be highly desirable for certain applications in which they have encountered unusual consumer acceptance.

A variety of techniques have been proposed for imparting a crimped structure to synthetic yarns but at the present time only one of these techniques is being practiced on a widespread scale. This procedure involves twisting the yarn, setting the twist, and untwisting the set yarn in a continuous operation without interruption between the individual steps. The continuous twisting and untwisting is accomplished by passing the yarn through a rotating body having some means for engaging the yarn to prevent free twist migration, rotation of the body imparting twist in one direction in the yarn on one side of the body and twist in the opposite direction on the other side thereof. Thus, an apparent or temporary twist is inserted in the yarn and is immediately removed therefrom as the yarn travels past the body. Spindles adapted for this operation have come to be known as "false twist" spindles in contrast to "true twist" spindles which rotate either the delivery or take-up yarn packages.

It is quite apparent that as the speed of rotation of the false twist spindle is increased, a higher number of turns per inch of temporary twist is imparted to the yarn, or else the yarn can be given the same number of turns while passing through the spindle at a higher linear speed. Recognizing this, workers in the art have attempted in various ways to effect a material increase in the speed of rotation of false twist spindles. For example, it has been proposed to utilize the principle of electric motors by constructing the spindle or yarn-engaging body as the armature of an electric motor. This proposal requires a separate electric motor for each strand of yarn being processed, which is prohibitively expensive for large scale production. Again, it has been proposed to float the spindle on jets of air inclined so as to exert a rotational as well as vertical force on the spindle. Such an arrangement requires extremely careful balancing of the forces involved, and of the jets acting on the spindle, which are usually quite numerous. Moreover, the consumption of compressed air in operating a large number of these spindles is enormous and compressed air is an expensive commodity. Conventional twister-spindles can, of course, be modified for operation at higher than usual speeds as by the use of improved bearings and other known expedients, but even when modified they have not been capable of obtaining speeds of much over 50,000 r.p.m. Unfortunately, at these speeds, which are not nearly so high as is desired, bearing failures are excessive and power consumption high despite the use of elaborate driving means.

2

An object of the invention is to provide a machine embodying a plurality of the high-speed false-twister units of the present invention, and including means for driving these spindles efficiently and economically.

5 A further object of the invention is to provide a machine of the type described wherein means are provided for reducing the load sustained by the high speed members of the driving arrangement.

10 Other objects and advantages will be apparent from the following detailed description of illustrative embodiment of the invention when read in conjunction with the accompanying drawings in which:

FIGURE 1 is an enlarged detail view of a spindle and housing unit of the present invention;

15 FIGURE 2 is a view in front elevation of the spindle and housing unit of FIGURE 1 in operative association with a swing assembly, the latter being shown partially in section to better reveal its details;

20 FIGURE 3 is a bottom plan view of the swing assembly taken generally along line 3—3 of FIGURE 2 with the supporting members of the assembly shown in section; and

25 FIGURES 4 and 5 are front elevation and bottom plan views, respectively, of a preferred form of a machine embodying the spindle and housing units of the invention and utilizing an improved drive for the units, the showing being diagrammatic in nature.

30 In general, the high speed false twister spindle of the invention comprises a small, lightweight tubular spindle rotatably supported adjacent the ends thereof in a housing. Bearings of special design are interposed between the housing and spindle to permit the attainment of extreme speeds of rotation without bearing failure, undesirable wear on parts or high frictional heat and means are provided for supplying limited amounts of lubricant to the bearing. In one practical embodiment, a plurality of spindle and housing assemblies are arranged in a single multi-position machine, the drive for the machine being particularly adapted for use with the assemblies including a main driving belt of sturdy construction and lighter weight secondary belts driven from the main belt and having driving contact with groups of spindles. Means are provided for further reducing the effective load placed on the secondary belt at any given point.

35 45 Alternative arrangements for journaling the spindle in the housing are contemplated.

40 Turning now to a detailed description of the invention, reference is made to FIGS. 1 of the drawings wherein a preferred embodiment of a single false twist spindle and housing unit is disclosed. Each unit, which may be given the general designation 10, consists essentially of a spindle blade 12, a housing 14, and journals or bearings 16, there between. Housing 14 is preferably in the form of a generally C-shaped metal block having a thick flat back portion 18 and a pair of legs 20a, 20b extending from the ends of the back portion the base or lower leg 20b being somewhat thicker than the upper leg 20a longitudinally of the block. The corners of the block may be rounded for sake of appearance. Coaxial, cylindrical bores 22a and 22b of equal diameter pass through legs 20a and 20b, respectively, the axis of the bores being parallel to the plane of back portion 18.

45 55 60 65 70 Each of the bores 22a and 22b is adapted to receive a cylindrical, plug-like bearing mount 24 which is fabricated from porous material, for example, sintered bronze or the like, the two mounts being generally identical in configuration and having a diameter slightly less than the diameter of bores 22a and 22b to facilitate their insertion therein. Inwardly of housing block 14, i.e. in the direction of the central opening of the C, mounts 24 are held in the bores by means of split-retaining rings 26, an annular spacing washer 28 being disposed between each ring

and mount to seal the mount from dust and the like. Towards the outer ends of the bores, the mounts are held against axial movement by means of bowed or dished retaining rings 30, annular spacing washers 32 being again provided between the rings and mounts as a dust shield and also to transmit thrust from the mounts to housing block 14. The retaining rings 26 and 30 engage internal grooves 33 and 34 respectively provided for that purpose in the walls of the bores. It is necessary that each of the bearing mounts 24 be accurately positioned radially as well as axially with respect to the bores and to this end a small cylindrical passage 36 extends transversely to the axis of the bores through the annular wall of each of legs 20a, 20b. A positioning pin 38 is inserted into each of these transverse passages until the internal end of the pin engages a recess 40 provided in the outer surface of each mount.

Each bearing mount 24 has a small central axially directed bore 42 coaxial with bores 22a and 22b, the internal ends of these small central bores being outwardly flared at a relatively large acute angle as at 44. Two substantially identical slots or channels 46 are cut into the internal wall of each mount bore 42, extending longitudinally the full length of the wall, with their axes parallel to the bore axis, and radially into the wall a distance equal to approximately one-half of the radial thickness of mount 24. There is disposed against the bottom wall of each slot 46 a thin metal strip or plate 48 roughly coterminous with the slot. The two slots in each mount 24 are preferably arranged with their center lines spaced 90° from each other and 135° from the axis of positioning pin 38. The slots are also preferably symmetrical with reference to a plane passed through the axis of bore 42 perpendicular to the plane of the back portion 18 of housing 14. Where the positioning pin is equidistant from the slots, as just described, the axis thereof will coincide with this plane.

Spindle blade 12 is of generally elongated cylindrical configuration having an axial bore 50 extending through the full length thereof for passage of the yarn, the mouth at the lower end of the bore being flared. Adjacent each end, the diameter of the blade is substantially reduced as compared to its normal diameter, the reduced end portions 52a, 52b serving as bearing surfaces or gudgeons for the spindle while the mid-portion 54 functions as a whorl. At the transition of the mid-portion to each end-portion is a shoulder 56 tapering at an angle roughly complementary to the angle of the flared internal ends 44 of bores 42 in mounts 24.

When the false-twister unit of the invention is assembled, the spindle blade 12 is supported by housing 14 with the reduced end portions received within the mount bores 42 so that the spindle bore is concentric with the housing bores 22a and 22b. The lower end 52b of the spindle blade terminates approximately flush with the lower of the external spacing washers 32 while the upper end projects above the upper of these washers and retaining ring 30 to accommodate a yarn-engaging cap or head 60, preferably formed of wear-resistant material. This cap includes a downwardly opening socket 62 fitting over the free end of the blade, a transverse flange 64 at the upper end of the socket portion, and two segments 66 projecting downwardly from diametrically opposed portions of the edge of the flange. A central axial aperture not shown is formed in cap 60. This aperture is, in effect, a continuation of bore 50, having a diameter substantially the same as that of bore 50. The edges of the aperture flange 64 and segments 66 are all rounded to minimize wear and tear on the yarn.

Reference has already been made to the presence in each of the bearing mounts of two spaced radial recesses 46 with metal plates 48 in the bottoms thereof. These recesses are adapted to receive identical bearing segments 70 which are disposed in pairs in the bearing mount and constitute journals for the reduced end portions of spindle blade 12. Segments 70 are formed of hard wear-resistant material, precious stones of natural or synthetic origin,

such a sapphire, being preferred, although highly wear-resistant metal can be substituted where increased frequency of replacement is permissible.

For the purpose of the invention two adjacent sides 72 and 74 constitute planar bearing faces, receiving the bearing load of the end portions 52a, 52b and tapered shoulders 74, intersects with the greater 72 at an obtuse angle approximately equal to that at which the ends of mounting bores 42 flare outwardly and complementary with the taper of shoulders 56. Side 76, opposite side 72, has a large convex radius of curvature and is adapted to seat against the metal strip 48 in the bottom of recess 46. The curvature of this side permits the segment to align itself in the recess with its bearing faces in proper contact with the corresponding surfaces of the spindle blade and avoids the necessity of forming the two opposite greater sides in exact parallel. Due to its curvature, side 76 can have only theoretical line contact with any plane surface against which it abuts and the function of metal plate 48 is to receive the concentrated load from the curved rear face of the segment and distribute it over the bottom of the radial recess in the porous mount. Where the segment and mount can be modified such that the load receiving and transmitting surfaces thereof are closely parallel to the axis of the spindle and to each other, plate 48 may be dispensed with.

Opposite to the inclined end face 74 is side 78 extending generally perpendicular to the greater bearing face 72. When positioned in the bearing mount this side is generally coterminous with the outer transverse end face of mount 24, as is readily apparent in FIGURE 1. The segment is completed by the two remaining faces 80 and 82 which are substantially parallel to each other and substantially perpendicular to all other sides.

The longitudinal and transverse dimensions of the segments are such that they are not wholly received within the recesses 46 but rather have their greater bearing faces 72 extending chordally with respect to the mount bore 42. This insures that the bearing load is borne by the segments rather than the internal surface of the bore. The diameter of the mount bores is sufficiently greater than that of the reduced end portions 52a, 52b of the spindle blade that a discernable clearance exists between the spindle surface and the surface of the bores. When the spindle is inactive, there is a small amount of lateral "play" in the spindle; however, rotational driving force, for instance of a belt 86, is transmitted to the spindle blade in such a way as to urge the spindle blade end portions into contact with the radial bearing faces 72 of the cooperating parts of the segments and away from the internal surface of mount bore 42. Similarly, the inclined bearing faces 74 are slightly raised above the flared end faces 44 of the porous mount.

From the foregoing descriptions, it will have been comprehended that each cooperating pair of segments 70 define a combination V-type radial and thrust bearing. The radial load is transmitted from the spindle through reduced end portions 52a, 52b, segments 70, and load distributing plates 48, to bearing mounts 24 and thence to the housing block 14. The inclined segment bearing faces 74 receive from the tapering spindle shoulders the axial thrust in either direction of the spindle and transmits the thrust through washers 32 and retaining rings 30 directly to the housing. While the radial bearing faces 72 of each pair of segments are preferably arranged at a right angle to each other, a different angle, except 180° can be used in lieu thereof.

The extreme high speeds at which the spindle of the invention is to be rotated make the provision of a lubrication system desirable if burned-out parts are to be avoided.

The above-described feature is accomplished in the present invention by giving the generally cylindrical porous bearing mount access to a supply of lubricating oil in order that the mount become permeated by such oil. As can be seen from FIGURE 1, such access is obtained

by forming in the interior wall in each of the bores 22a, 22b an annular recess 90 extending into the housing legs 20a, 20b. Each of the annular recesses 90 is in communication with an oil reservoir chamber 92, one of the chambers being formed adjacent the upper end of the back portion 18 of the housing block and the other adjacent the lower end thereof. Annular recesses 90, and preferably the reservoir chambers 92 as well, are filled by oil-absorbent felt, indicated at 94, the presence of the felt retarding the flow of oil through the sintered bearing mount and tending to prevent a condition of over-lubrication. Chambers 90 may be conveniently obtained by drilling into back portion 18 of the housing from the rear face thereof and pressing a plug 95 into the end of the opening.

Any appropriate means may be provided for filling the oil reservoir chambers, such as a passageway 96 extending upwardly from the upper chamber to the top face of housing block 14 and a passageway 98 extending upwardly and outwardly from the lower reservoir chamber to the back face of the block.

It is well known that yarn undergoing bodily rotation tends to balloon outwardly due to centrifugal force, which may lead to yarn entanglement where a plurality of strands of yarn have closely adjacent paths. Objectionable ballooning may be prevented by having suitable guide means restrain the yarn after passage around the yarn engaging head. It is advantageous from the standpoint of simplicity in assembling the false-twister spindle units of the invention into a machine for each unit to carry its own yarn guide which may take the form of a length of stiff wire 100 having a loop or pig-tail 102 at the upper end thereof in axial alignment of the bore 50 of spindle 12 the lower end of the guide wire being attached to the upper face of the housing block, as at 104.

Up to this point, the description of the invention has been confined to a single false-twister spindle unit existing in the abstract, so to speak, that is, independent of any particular combination of elements for mounting or supporting the units in an actual machine. This mode of description was adopted because of the fact that the unit is capable of being mounted in any one of several ways. One such way is illustrated in FIGURES 2 and 3 and is intended to be employed primarily when a new machine, ordinarily including a large number of units, is to be constructed. In this arrangement, the numeral 108 indicates a horizontal frame member of the twisting machine supported in the usual way by means not shown and on which a number of the false-twister spindle units are to be mounted. At appropriate spaced points along the length of frame member 108, a swing post 110 is fixedly secured thereto, the lower end of the post passing through an aperture provided in the member and threadedly engaging a nut 112. Nut 112 is opposed on the opposite side of member 108 by a collar 113 integral with post 110. Swing post 110 is surrounded over the major portion of its length by a sleeve 114 that is rotated freely on upper and lower bushings 116. Encircling sleeve 114 is a torsion spring 118 having one of its ends fixedly connected to the sleeve and the other held in engagement with a diametrical recess 120 formed in the upper end of the post by means of an annular C-ring 122. A second C-ring 123 is spaced on post 110 inwardly of ring 122 to receive the thrust from sleeve 114 and prevent undue axial play in the sleeve. The post, sleeve and spring may be enclosed by a cover 124 having a friction fit with the base of the sleeve.

The false-twister spindle unit 10 is supported for pivotal movement about the swing-post on a swing-plate 126. Adjacent one end of this plate is an aperture not visible in FIGURE 5, which is in press-fitting engagement with the lower end of sleeve 114. A second aperture 128 (see FIGURE 1) is provided adjacent to the other end of the plate for the reception of an extension 130 projecting below the bottom leg of the housing block and having

reduced dimensions as compared to the housing. The entire spindle and housing unit is held against vertical movement with respect to swing-plate 126 by means of a dished retaining ring 132 engaging at its inner end a circumferential recess in the extension and bearing at its outer end against the undersurface of swing plate 126. Upon removal of the retaining ring the unit may be lifted from the swing plate to facilitate repair and/or replacement.

The primary function of the swing assembly is to support the spindle unit for pivotal movement toward and away from driving belt 86 adapted to engage the center whorl portion of spindle blade 12 to rotate the same. A fragment of such a belt is shown in FIGURE 2. When the machine is assembled, torsion spring 118 is pretensioned so as to urge the blade into contact with the driving belt, the tension being sufficient to prevent slippage between the belt and spindle. In order to facilitate disengagement of the spindle from the driving belt, utilization may be made of a disengaging lever 142. As can be seen in FIGURE 3, this lever is pivotally connected at one end to frame member 108 by means of a stud 144 and is formed at the other end with a handle 146 projecting downwardly below the frame member. Intermediate the pivoted end and handle 146 is a turned-up ear 148 which is adapted to engage a down-turned flange 150 at the rear edge of swing plate 126. As the disengaging lever is moved clockwise in FIGURE 6, ear 148 engages flanges 150 to shift the unit slightly away from the driving belt to an inoperative position shown in dotted lines. When pivoted to the full extent permitted by swing post 110, lever 142 is in an "over-center" position, shown in dotted lines, where it is urged by swing spring 118 through swing plate 126 against post 110. When lever 142 is in "over-center" position, unit 10 is maintained with the spindle whorl portion out of contact with the driving belt even when the lever is released. Movement of the lever counter clockwise past "dead center" permits swing spring 118 to act on swing plate 126 to pivot the unit back into belt engaging position.

It will be appreciated by those skilled in the art that a plurality of spindle and housing units and associated swing assemblies may be organized in the manner customary with twisting machines, that is in two parallel rows, one on each side of the machine, with an endless driving belt located between the rows, driving all of the spindles in both rows, the belt, in turn, being driven from a high speed electric motor. This arrangement, however, presents certain difficulties from a practical point of view. While the torque requirement of an individual unit is quite low compared to a conventional twister spindle, the total or aggregate requirement for a large number of units, say 100, is fairly high.

If the spindles were to be driven directly from a single belt at the speeds contemplated, the linear rate of travel of the belt would be higher than can be tolerated with a large, heavy belt such as is required to transmit the total power load of the machine. A heavy belt ordinarily has irregularities in its surface and tends to whip at high speeds so that it can be held against the whorl portions of the spindle blade only by strong swing pressure. Thus, it has not been possible to find a large, heavy belt from among those presently commercially available that will operate satisfactorily.

For this reason, although the construction of a machine embodying the spindle units of the invention along conventional lines is not considered completely outside the realm of possibility, a modification of the conventional drive to meet the peculiar needs of the invention is considered preferable. One modification that has been found satisfactory is shown in FIGURES 4 and 5, it being understood that the illustration is quite diagrammatic in nature and omits all mechanical details. In this figure, the numeral 152 designates a primary driving belt which is of the heavy durable type normally used in twisting

machines, and is arranged in the normal fashion, i.e., in an elongated endless loop with large diameter pulleys 154 at each end of the loop. One of the pulleys is driven by an electric motor, not shown, while the other functions as an idler. There is disposed along each of the two straight stretches of the loop a plurality of pulleys 156. Contacts between the main belt and all of pulleys 156 is insured by means of small idlers 157 engaging the opposite side of belt 152, there being one such idler between each pair of pulleys 156.

Pulleys 156 are of the compound type, having a large diameter portion 158 and a small diameter portion 160, the primary driving belt having driving contact with the small diameter portion. The large diameter portion of the pulleys is in driving contact with a high-speed secondary driving belt 162. Preferably, more than one of the secondary belts is used, each having a path in the shape of an elongated endless loop and encompassing a plurality or group of the compound pulleys on one side of main belt 152. The end or terminal pulleys of the group are in contact with the secondary belt through an arc of roughly 180° while the remaining intermediate pulleys have opposite sides in tangential contact with the belt. In the illustrated arrangement, only one plurality or group of compound pulleys and associated secondary driving belts is shown on each side of the main driving belt, but it will be appreciated that a number of these groups can be utilized. Also, the number of pulleys in each group may vary from that specifically illustrated. The compound pulleys in each group are spaced at intervals along the straight stretch of the main driving belt so that the secondary belt upon leaving one pulley is unsupported for a distance before contacting another pulley. Between each pair of adjacent pulleys 156, a group of the spindle units 10, of the invention are arranged in a straight line adjacent the unsupported stretch of the secondary belt so that when in operative position the whorl portions of the spindle are in driving contact with the belt. The number of spindles between the pairs of pulleys and contacting a single unsupported stretch of the secondary belt may, naturally, be varied.

This spindle driving arrangement has characteristics particularly desirable for high speed spindles. The main belt has no direct contact with the spindle blades; the fact that this belt may not run smoothly is, therefore, immaterial. A large heavy main belt, capable of transmitting the total power required for all units, can, hence, be utilized without deleteriously affecting the performance of the machine. The maximum tension in secondary driving belt 162 need be only sufficient to transmit the power being consumed by the group of spindle units 10 mounted between an adjacent pair of pulleys 156 as it is given fresh driving impetus by a pulley 156 before encountering the next group of units. Therefore, spindle driving belt 162 can be thin, flexible and readily capable of high speed travel. Such a thin, flexible, low-tension belt requires only a small pressure against the spindle whorl in a normal direction to impart rotation to the spindle blade. Operation of the machine with light belt pressure results in the further advantage of light loading of the spindle bearings.

In brief, the organization illustrated in FIGURES 4 and 5 divides the drive into a low-speed, high-load stage and a high-speed, low-load stage, and the load transmitting elements for each stage can be selected to meet the particular requirements of that stage and need not be expected to function over an almost impossible range of conditions. It will be understood that in this organization the spindle units shown diagrammatically and indicated by the nu-

meral 10 will actually be in the form of the complete assembly of FIGURES 2 and 3.

The false twist spindle unit of FIGURES 2-5 is operated in the following manner. To thread the spindle blade, lever 142 is pivoted towards swing post 110, pivoting swing plate 126 and spindle unit 10 away from belt 162 (35' in FIGURES 2 and 3). A suitable threading needle or snake is attached to a strand of yarn from a suitable supply package, not shown, and passed through the spindle bore 59, drawing the yarn through the bore and opening 63 in cap 60. The strand of yarn is then wrapped around and under flange 64 so that when threaded through yarn guide 102 it is retained beneath the down-turned lip 66. Next, the strand is attached to any suitable yarn take-up mechanism, not shown. By means of the cooperating ball and socket the position of housing may be adjusted relative to plate 126 until the pairs of bearing segments 70 are disposed symmetrically about a plane passed through the spindle blade axis perpendicular to the spindle driving belt. Segments 70 are, of course, on the opposite side of the spindle blade from the belt. Alternatively, the housing may be positioned so that the radial bearing face of one segment of each pair is parallel to the belt while the same face of the other segment is normal to the belt on the side of the spindle in the direction of travel of the belt. When the strand is properly threaded, lever 142 is then pivoted away from post 110 whereupon spring 118 pivots swing plate 126 about post 110 until whorl portion 54 of the spindle blade contacts the driving belt.

For this reason, the form of the invention illustrated herein should be considered as exemplary only, the scope of the invention being defined by the hereunto appended claims rather than by what is specifically illustrated and described.

What is claimed is:

1. In a machine for false twisting a strand of yarn, in combination, two main pulleys at laterally spaced points, means for rotating at least one of said pulleys, a thick, relatively rigid main driving belt encircling said two main pulleys in an elongated endless path having two straight stretches, a series of compound pulleys disposed at spaced points along at least one stretch of one path of said main belt, each of said compound pulleys having a large diameter surface and a small diameter surface, the latter being in driving contact with one side of said main belt, a single thin, relatively flexible secondary driving belt driven by the large diameter surfaces of said compound pulleys along said stretch, and a plurality of false twister spindles arranged between each pair of compound pulleys in said series in driving contact with said secondary driving belt.
2. A machine as in claim 1 including an idler pulley disposed between alternating pairs of said series of compound pulleys, said idler pulleys being in contact with the side of said main belt opposite to said compound pulleys.
